UNITED STATES PATENT OFFICE.

CHARLES C. REDMOND, OF LOS ANGELES, CALIFORNIA, ASSIGNOR OF ONE-HALF TO
ALEXANDER M. FLEISHER, OF LOS ANGELES, CALIFORNIA.

CAN OPENER AND CLOSURE.

1,316,508.

Specification of Letters Patent. Patented Sept. 16, 1919.

Application filed April 12, 1919. Serial No. 289,573.

To all whom it may concern:

Be it known that I, CHARLES C. REDMOND, a citizen of the United States, residing at Los Angeles, in the county of Los Angeles 5 and State of California, have invented new and useful Improvements in Can Openers and Closures, of which the following is a specification.

This invention relates to can openers and 10 has for its object the provision of a device adapted for use in connection with cans such as cans of evaporated milk in which it is necessary, in order to remove the contents, to punch two holes, one for pouring out the 15 contents and the other to permit the entrance of air, the construction of the device being such that at one operation two holes are punched and that when the can is standing idle the penetrating members used 20 for punching may be inserted within the punched holes to form closures therefor to exclude dust and dirt and to prevent access by flies or other insects.

An important object is the provision of a 25 device of this character which includes a circular cover having a depending flange and which is adapted to be engaged upon the top of the can to be punched, the penetrating members being carried by this cover 30 and the cover serving to exclude dust and dirt even though the penetrating members be not engaged within the punched holes.

A further object is the provision of a device of this character which will be very 35 simple and inexpensive in manufacture, highly efficient and durable in use, sanitary in service, and a general improvement in the art.

With the above and other objects and ad- 40 vantages in view, the invention consists in the details of construction to be hereinafter more fully described and claimed, and illustrated in the accompanying drawings, in which—

45 Figure 1 is a longitudinal sectional view through my device showing it initially engaged upon a can,

Fig. 2 is a similar view, showing the penetratin members driven into the can, and

50 Fig. 3 is a plan view thereof.

Referring more particularly to the drawings the letter A designates a cylindrical can, for instance an evaporated milk can. My device comprises a cylindrical cover

member 20 which is formed as a circular 55 plate having a depending flange 21.

The cover 20 is provided at its center with an upwardly extending cylindrical post 22 terminating in an enlarged head 23. The cover is also provided at diametrically opposite points with circular holes 24. Mounted for vertical sliding movement upon the post 22 is an elongated strip or bar 25 which is provided adjacent its ends with penetrating members 26 terminating at their upper ends in knobs 27, and having their lower portions sharpened to provide points adapted to pass through holes 24 in the cover 20.

The use of the device is as follows:—

The cover 20 is placed upon the can 70 whereupon the points of the penetrating members 26 will merely rest upon the top of the can and the bar 25 will be disposed substantially in contact with the underside of the head 23 on the post 22, as clearly 75 shown in Fig. 1. The operator then presses upon the knobs 27 and forces the penetrating members 26 through the top of the can whereupon the bar or strip 25 will slide downwardly upon the guide post 22 and 80 into engagement with the top of the cover 20. When the cover and its associated parts are subsequently removed two holes will be left in the top. When the can is not in use, the cover is replaced and the members 26 re- 85 disposed within the holes in the can, as in the first described form.

From the foregoing description and a study of the drawings it will be seen that I have provided a device which is very simple, which is inexpensive, and which may be quickly and easily used for punching a pair of spaced holes in the top of a can, which will also serve as means for closing the holes when the can is not in use to prevent access 95 of dust, dirt and insects, and which will as a consequence be sanitary and efficient in use.

While I have shown and described the preferred embodiments of my invention, it 100 is of course to be understood that I reserve the right to make such changes in the form, construction, and arrangement of parts as will not depart from the spirit of the invention or the scope of its subjoined claims. 105

Having thus described my invention, I claim:

1. A device of the character described

comprising a flanged cover adapted for engagement upon the top of a can, an upstanding post at the center of said cover, a transverse bar slidably associated with said post, and a pair of penetrating members carried by the ends of said bar and extending through openings formed in said cover.

2. A device of the character described comprising a cover provided with a flange and adapted for concentric engagement upon the top of the can, an upstanding post at the center of said cover and having an

enlarged head, a bar extending transversely of said cover and slideable upon said post, a pair of penetrating members carried by said bar adjacent the ends thereof, said penetrating members extending toward the free edge of said flange; and knobs on the ends of said bar serving as hand engaging members, said cover being provided with holes for the passage of said penetrating members.

In testimony whereof I affix my signature.

CHARLES C. REDMOND.
